(57) **CLAIM**

The ornamental design for a vehicle tail light, as shown and described.

DESCRIPTION

FIG. 1 is a perspective view of a vehicle tail light;

FIG. 2 is a left side view thereof;

FIG. 3 is a front view thereof;

FIG. 4 is a right side view thereof;

FIG. 5 is a back view thereof;

FIG. 6 another perspective view thereof; and,

FIG. 7 is a top view thereof.

The broken lines shown in the drawings represent portions of the vehicle tail light that form no part of the claimed design.

The claim includes a second embodiment comprised of a mirror image of a vehicle tail light as shown in FIGS. 1-7. The mark “*αREX*” shown in the drawings is an unregistered trademark of Arex Industries, Inc.
